UNITED STATES PATENT OFFICE.

PAUL R. MOORE, OF PORTLAND, TENNESSEE.

LOOSE-LEAF BINDER.

Application filed July 23, 1921. Serial No. 487,038.

To all whom it may concern:

Be it known that I, PAUL R. MOORE, a citizen of the United States, residing at Portland, in the county of Sumner and State of Tennessee, have invented certain new and useful Improvements in Loose-Leaf Binders, of which the following is a specification.

This invention relates to improvements in loose leaf binders and has as its object to provide a binder which will present advantages over the binders now in use. In the ordinary binders it is usually necessary to bodily remove a locking member when it is desired to open the binder, and to replace this member when the binder is to be again closed.

In other types of binders it is necessary to make use of a key for locking and unlocking the binder. Both of these constructions, however, present the disadvantage that considerable time is required to manipulate the locking devices, and where removable locking members or keys are employed, these are liable to be lost or mislaid causing inconvenience and a further loss of time. It is therefore the primary object of the present invention to provide a binder adapted to be securely locked and capable of being instantly unlocked by the manipulation of an element which constitutes a permanently connected part of the device and which cannot therefore be misplaced or lost.

Another object of the invention is to so construct the binder that when the sections comprising the same are pressed together to adapt the binder to retain the leaves inserted therein, the said members will be automatically locked regardless of the thickness of the assemblage of leaves, within reasonable limits.

In the accompanying drawings:

Figure 1 is a perspective view of the binder embodying the present invention, the covers of the same being shown open and all of the leaves except one being removed to better illustrate the construction of the invention.

Figure 2 is a vertical transverse sectional view through the binder, the covers being shown in closed position and the leaves omitted, the relatively adjustable sections of the binder being illustrated in full lines in closed position and in dotted lines in open position.

Figure 3 is a plan view of the binder with

the covers and leaves removed, certain of the parts being shown in section.

Figure 4 is a horizontal sectional view taken substantially on the line 4—4 of Figure 2 looking in the direction indicated by the arrows.

Figure 5 is a vertical longitudinal sectional view taken substantially medially of the binder, parts being shown in elevation.

In the drawings the numeral 1 indicates in general the back of the ledger or other book of which the binder embodying the invention forms a part, and the numeral 2 indicates the covers of the ledger, one of the ledger leaves being shown in Figure 1 of the drawings and indicated by the numeral 3 and being provided with the usual notches 4 for engagement with the posts of the binder as will presently be explained.

The binder comprises a back plate which is indicated by the numeral 5 and to the outer side of which the back 1 is secured in any suitable manner. The back plate 5 has its end portions bent upwardly at right angles to provide end members which are indicated by the numeral 6 and which in turn have their upper edge portions formed with over-turned flanges 7 as best shown in Figure 5 of the drawings. The binder further comprises a pair of relatively adjustable side members indicated in general by the numeral 8 and each comprising wings 9 and 10 which occupy planes at right angles to each other, the wings 9 occupying a plane slightly spaced from the plane of the back plate 5 as shown in Figure 2. The wings 9 are further slidably disposed upon cross pieces 11 and 12 which are secured to the back plate 5 and project at their ends beyond the lateral edges of this plate. The wings 10 of the side members 8 are provided at their ends with right angularly extending end pieces 13 which at their upper edges are slidably engaged within and guided by the overturned flanges 7 of the ends 6 of the back plate. Studs 14 are provided upon the inner faces of the said ends 6 and project into slots 15 formed in the end pieces 13 as best shown in Figure 3 of the drawings. The engagement of the studs 14 in the slots 15 serve as a further means for guiding the side members 8 in their relative sliding movement upon the cross pieces 11 and 12, and also as a means for preventing complete separation of the side members when the binder is unlocked and these members are forced

apart by means to be presently described. It will be observed by reference to Figure 2 of drawings that the covers 2 are hingedly connected as at 16 to the upper edges of the 5 wings 10 of the side members 8.

In order that the loose leaves to be bound may be retained within the binder, leaf-supporting posts are provided and each of these posts, which is indicated in general by the 10 numeral 17, comprises a tubular section 18 which is exteriorly cylindrical. Each post further comprises a section 19 which is slidably telescopically fitted into the respective post section 18. At their relatively remote 15 ends, the post sections 18 and 19 are secured to bars 20 which are supported by brackets 21 in turn secured to the inner sides of the wings 10 of the two side members 8. It will now be evident that when the side members 8 are relatively separated, the loose leaves may be engaged on the posts after which the side members 8 are again brought together. Likewise in removing the leaves the sections will be relatively separated and 20 the leaves will be slipped off from the posts. It will be observed by reference to Figure 2 of the drawings that the brackets 21 are offset in an inward direction so as to accommodate the inner or hinged edges of the covers 2 when the covers are closed.

In connection with the side members 8, the invention contemplates the provision of means for locking these members against separation when they are brought toward 35 each other in closing the binder, and the provision of other means for automatically forcing the members apart when the locking means is released. The locking means comprises a ratchet wheel 22 which is rotatably 40 mounted upon a stub spindle 23 upon the upper or inner side of the back plate 5 preferably at a point midway between the ends of said plate. The links 24 are pivotally connected as at 25 to the ratchet wheel 22 at 45 diametrically opposite points and at their opposite ends are pivoted as at 26 each to a respective one of the side members 8. The links 24 extend substantially tangentially with respect to the ratchet wheel 22 and it 50 will therefore be evident that when the side members 8 are respectively adjusted, the link connections 24 will impart rotary motion to the ratchet wheel 22. The teeth of the ratchet wheel are indicated by the numeral 27 and extend in a series part way about the periphery of the ratchet wheel, and in connection with the ratchet there is 55 provided a pawl indicated in general by the numeral 28, the pawl being pivotally mounted as at 29 upon the upper or inner face of the back plate 5 and being provided at one side of its pivot with a tooth 30 for coaction with the teeth 27 of the ratchet wheel 22.

At the other side of its pivot the pawl is extended to provide a finger lever 31 which

extends longitudinally of the back plate 5 and works through a slot 32 formed in one of the end pieces 6 of the said back plate, the lever 31 having its portion which projects beyond the end of the back plate 70 formed to provide a finger piece 33. A spring 34 is connected at one end of the back plate 5 and at its other end to the lever 31 and yieldably holds the lever in position with the tooth 30 engaging the teeth 27. It 75 will now be evident that when the binder is closed by forcing the side members 8 toward each other, the ratchet wheel 22 will be rotated and the teeth 27 thereof will ride past the tooth 30 until, when the ratchet wheel 80 has ceased to rotate, the said tooth 30 will remain in locking engagement with one of the teeth 27 and as the ratchet wheel is thus restrained against backward rotation, the side members 8, through the link connections 24 85 with the ratchet wheel, will be held against relative separation. However when the finger piece 33 of the lever 31 is pressed to the left in Figure 4 of the drawings the lever will be swung against the tension of the 90 spring 34 to substantially the dotted line position shown in said figure, and the ratchet wheel 22 will then be released for rotation, and the automatic expanding means employed will be free to act.

The expanding means above referred to 95 comprises two or more coiled springs 35 which are fitted at their ends over posts 36 upon the wings 10 of the side members 8 and which bear at their opposite ends against 100 the said wings. As the springs 35 are normally under compression, their tendency to expand will serve to force the side members 8 apart the instant the pawl 28 is actuated to release the ratchet 22. In order to protect 105 the springs 35, housing sleeves 37 are disposed to fit loosely over the springs and the adjacent ends of the posts 36.

From the foregoing description of the invention, it will be seen that there is provided a binder into which the leaves may be readily introduced and which binder will be automatically locked to retain the leaves, when the side members thereof are closed. It will also be evident that the binder will be 110 automatically opened at the instant the pawl 28 is actuated to release the ratchet 22.

Having thus described the invention, what is claimed as new is:

In a loose leaf binder, a back plate, leaf-binding members slidably supported in spaced relation to the plate, the back plate having an upstanding end, a rotatable ratchet wheel mounted upon the inner face 120 of the back plate and in the space between the same and the leaf-binding members, links pivotally connected to the said leaf-binding members and at diametrically opposite points to the said ratchet wheel, the upstanding end of the back plate being pro- 125 130

vided with an opening, a pawl pivoted upon the back plate and having a toothed end for coaction with the teeth of the ratchet wheel, the opposite end portion of the pawl 5 extending through the opening in the said upstanding end of the back plate and being provided beyond said upstanding end with a finger piece, and a spring connected to the pawl and to the back plate and yieldably holding the toothed end of the pawl in engagement with said ratchet wheel.

In testimony whereof I affix my signature.

PAUL R. MOORE. [L.S.]
